UNITED STATES PATENT OFFICE.

PAUL G. TISMER, OF NEW YORK, N. Y.

FLUID-PRESSURE ENGINE.

1,103,104.

Specification of Letters Patent. Patented July 14, 1914.

Application filed August 2, 1913. Serial No. 782,618.

To all whom it may concern:

Be it known that I, PAUL G. TISMER, a subject of the German Emperor, residing in the borough of Manhattan, city, county, and State of New York, have invented certain new and useful Improvements in Fluid Pressure Engines, of which the following is a full and clear specification.

This invention relates to fluid-pressure engines of the reciprocatory type and is—10 as here shown—embodied in a double acting pile driving hammer.

It is one of the objects of this invention to produce an unrestricted striking stroke 15 permitting the full force of the stroke to be expended prior to the reversal of the motive fluid.

It also provides for the shifting of the reverse valve by means of the exhaust of the 20 fluid pressure to make certain of its movements.

It further provides that the opening of the exhaust passages is controlled by recesses in the main piston for the purpose 25 of relieving the device of all pressure when said exhaust ports are in line with said recesses.

It is further provided that the flow of the 30 fluid pressure is at all times in one direction, employing thereby the so-called "uniflow" system which permits, as is well known, a very high efficiency in a single cylinder approaching, if not equaling, that of the triple expansion engine.

35 It further provides a cut off valve to permit the use of the fluid pressure expansively to accomplish still higher economy.

Further, for purposes of control, a hand 40 valve is provided to change the point of cut-off, to permit the delivery of blows either hard or soft to meet the conditions that may be encountered when driving piles in various kinds and depths of soils.

Furthermore, the upward or return stroke 45 is here absorbed in full by means of fluid pressure, *i. e.* what remains in the upper part of the main cylinder after the exhaust has been uncovered and then at atmospheric pressure, will be entrapped and compressed 50 to absorb the return stroke.

Further: the working stroke is made to be of a variable nature by means of the remaining exhaust fluid similarly entrapped on the down stroke, but the total pressure 55 here produced is but of 5 pounds at the most and utilized to shift the cut-off valve

to a greater or lesser degree of cut-off; or not shifting it at all, or closing it altogether depending upon the opening less or more, or opening none or closing entirely, of a hand controlled opening affording an outlet to the so entrapped fluid under the pressure exerted by the downgoing piston. In this manner the return stroke is positively postponed until the striking stroke has come to a full rest a function quite contrary to other devices built heretofore for similar purposes, and in which the full force of the striking stroke was never available because the reverse valve there used is "on" full, before the piston has delivered its blow since in those devices the piston travel is directly responsible for the actuation of the reverse valve. Such back pressure as may here be created when the exhausting fluid shifts the reverse valve is but nominal, never exceeding one pound per square inch since the exhaust valve is very light and of the balanced piston type. Such back-pressure as is developed beneath the downgoing piston is again but nominal since its only duty is to shift the cut-off valve, which is also of the piston type and balanced. This valve is held in the "open" position preferably by means of the pressure of the motive fluid but since the two ends of this valve are of different diameters the "live" side being but a small fraction of that of the other, not over 5 pounds maximum will be developed at this point, depending upon the length of cut-off desired; a greater choking of the outgoing fluid at the regulating handvalve will cause a greater rise of pressure since then it will take a greater length of time to permit the accumulated pressure to fall by outflow into the atmosphere. If preferred, a spring may be used to shift the cut-off valve to the "on" position instead of the pressure fluid; the pressure fluid here used merely has that function.

Although the device is here shown a pile-hammer for the purpose of driving all manner of piles, the motive unit is equally well adapted for pumping purposes and if connected "direct" to a single acting pump, no changes need to be made in the power end; the device then acting with any desired cut-off, or without cut-off, depending upon adjustment. When a double acting pump is actuated "direct" with the power end of this device, the up stroke needs to be the same as the down stroke, requiring

alteration readily understood and needing no further description.

For carrying out these and other objects, as will appear in the specification, there is provided a motive unit of the type in which a piston reciprocates in a cylinder, the piston being adapted to transmit power for any desired service for which an engine of this character is suitable. According to the present embodiment, the admission of motive fluid is controlled by a main valve and a supplementary cut-off valve. The position of the main valve is controlled by the exhaust motive fluid coming from the cylinder to the valve casing in which the main valve is located. The position of the cut-off valve is preferably controlled through the balanced action of the fresh motive fluid on a relatively small surface and the fluid displaced from the cylinder on the power stroke of the piston.

In the accompanying drawings in which like reference characters denote corresponding parts, Figure 1 is a view in elevation partly broken away to show the underlying structure; Fig. 2 is a diagrammatic view showing the piston at the beginning of its down stroke, the motive fluid being admitted through the cut-off valve and the main valve to the upper end of the cylinder. Fig. 3 is a view similar to Fig. 2 showing the piston adjacent the end of its power stroke. Fig. 4 is a view similar to Figs. 2 and 3, showing still another position of the parts in which the piston has arrived at the end of its down stroke uncovering the proper exhaust port. Fig. 5 is a fragmentary sectional view through the cylinder and valve casings. Fig. 6 is a detail view showing the arrangement whereby the control of the admission of live motive fluid to the lower half of the cylinder may be governed by the cut-off valve under the action of the fluid displaced from the cylinder during the power stroke.

Referring more particularly to the drawings and to the embodiment shown therein, an instrumentality to which power is to be delivered is represented in the present embodiment by a ram 1 employed in driving piling under the action of a motive unit 2. The motive unit 2 in this instance embodies a cylinder 3, and a piston 4, reciprocating therein, said piston being provided with a piston rod 5 which extends through the head of said cylinder. The ram 1 may be guided in any suitable manner as by means of a follower 6^a engaging guiding rods 7^a, the latter being connected to and supporting a head 8^a. In order to provide suitable and efficient means for enabling the piston 4 to control the exhaust without employing objectionable valve mechanism, and to eliminate the violent reversals by reason of the strokes which are but defined in part, the

length of said piston is preferably constructed approximately one-half the length of cylinder 3 and said cylinder is provided with exhaust ports 6 and 6' suitably disposed between the ends of the cylinder to co-operate with recesses 22 and 35 in the piston in the manner to be hereinafter pointed out. The supply of motive fluid to the cylinder is controlled by a main or reversing valve 7 and a cut-off valve 8, both being of the balanced piston type and the former arranged to reciprocate in a valve chamber 9 and the latter in a valve chamber 10. The motive fluid which may be steam, compressed air, or any other form of fluid actuating means, enters the cut-off valve chamber from a supply pipe 11 and into an annular recess 12 in the wall of chamber 10. The cut-off valve 8 is provided with a valve disk 13 which is normally held in the position shown in Fig. 2, by pressure of the fluid in chamber 31, thus permitting the motive fluid to pass from the recess 12 as indicated by the arrows, and through a port 14 into a duct 15 which leads to an annular recess 16 in the wall of the reversing valve chamber.

Under the conditions shown in Fig. 2, the reversing valve 7 which in the preferred embodiment comprises disks 17, 18 and 38 is at the extreme left, so that disks 17 and 18 of the valve form a direct passage to a passage 19 which leads from a port 20 in the valve chamber 9. Said passage 19 terminates below in an annular recess 21 in the upper end of the cylinder 3 and as here shown, conveys live motive fluid to the space above the piston 4, causing the latter to be forced downwardly. Intermediately of its ends and preferably adjacent its central transverse plane, said cylinder is provided with exhaust ports 6 and 6'. The piston 4 in passing by the exhaust port 6 entraps a certain volume of fluid then at atmospheric pressure in the lower end of the cylinder. As the piston descends, the fluid below it is forced through an annular recess 25 adjacent the bottom of the cylinder 3 and into a passage 26 which leads to an annular recess 27 in the valve chamber 9, so that the exhaust remnant which is displaced from the lower end of the cylinder 3 is permitted to pass through the valve chamber 9 between the valve disks 18 and 38 to a duct 28 leading into the space to the right of the disk 13 of the cut-off valve. The outlet for this portion of the cut-off valve chamber, is located at 29 and as may be seen by reference to Fig. 6, is controlled by a valve comprising valve seat 29' and valve 30, having a hand wheel as shown. The speed at which the entrapped fluid discharges can be governed by the control valve 30 which is manually adjustable to vary the outlet to the open air. It will be seen

therefore, that if the valve 30 is partly closed, the fluid entrapped beneath the piston 4 will be compressed and will exert a pressure preferably about 1 pound per square inch, on the lateral surface of the valve disk 18, so that the cut-off valve 8 will be forced from the position shown in Fig. 2 to the cut-off position shown in Fig. 3.

10 The valve 7 is thrown to the right (as hereafter explained) before the fluid displaced from below the piston 4 has been completely expelled through the discharge outlet valve 30, at which stage the cut-off valve 8 is still in the position shown in Fig. 3, but the reversing valve 7 is in the position shown in Fig. 4. In this position of the parts a supplementary duct 28* will convey the entrapped air and fluid from the valve chamber 9 to the valve chamber 10 and thus to the conduit 29. When the entrapped fluid has entirely passed the valve 30 to the air, the cut-off valve 8 will be returned to the position shown in Fig. 2, by reason of the pressure 25 sure exerted by live motive fluid within the chamber 31 against the stem of the cut-off valve 8, said fluid of about one pound per square inch being introduced to the chamber 31 by means of a bleed passage or conduit 32.

When recess 22 in piston 4 uncovers port C in its downward travel, the reversing valve 7 will be shifted over from the position shown in Fig. 2 to the position shown 35 in Fig. 4, by the exhaust motive fluid passing out from the upper part of the cylinder 3, through the exhaust port 6, into an exhaust conduit 23 which is connected to the left-hand end of the valve chamber 9 and connects the exhaust motive fluid to a point to 40 the left of the valve disk 17 of the reversing valve 7. It will be noted that the valve disk 17 in the position shown in Figs. 2 and 3, co-operates with an annular flange 33 to 45 close a port 34 in the valve chamber 9 which leads to a conduit 24. As soon, however, as the pressure back of the valve 17 rises sufficiently, i. e. to about 1 pound per square inch pressure, the reversing valve will be 50 shifted from the position shown in Fig. 2 to the position shown in Fig. 4, when the exhaust fluid is free to pass into the exhaust conduit 24. When the pressure of the fluid in chamber 10 to the right of disk 13, has 55 dropped until the pressure in chamber 31 against the end of the valve stem is again sufficient to throw the cut-off valve 8 to the right then the motive fluid will pass from the supply pipe 11 through the cut-off valve 60 chamber, duct 15, into the valve chamber 9, and thence into the passage 26 which delivers it below the piston 4, that is to say, although reverse valve 7 had been shifted at 65 the moment of uncovering of the exhaust ports, the motive fluid has not been again admitted until the piston 4 had come to rest on its down travel, whether that was an instant rest as it might be with an unyielding pile or a delayed rest, delayed by the ram following the pile. The piston 4 will now rise under the pressure of the live motive fluid, and inasmuch as the valve disk 17 closes the upper end of conduit 19, a certain amount of fluid will be entrapped. This entrapped fluid will be compressed and aids the fresh motive fluid in the succeeding down stroke of the piston. That is to say, the piston covers the exhaust port 6 soon after it starts on its upward stroke so as to form a fluid cushion absorbing in total or in part the force of the upward blow and then using the energy amounting to not less than fifty pounds per square inch stored up by the compression of the entrapped fluid in assisting the live motive fluid to impel the piston on the subsequent down stroke. By this means, not only is jarring eliminated on the up strokes but also there is a substantial saving in motive fluid used. During the upstroke of the piston, the upper part of the cylinder is effectively closed at port 20 (Fig. 4). The cut-off valve 8 is affected during such upward movement only by the constant force of the fluid acting on the rear of the valve through bleed passage 32 and 95 the valve remains in a wide open position. As a piston 4 farther moves upwardly, a recess 35 in the piston will come into register with the exhaust port 6', thus permitting the motive fluid to exhaust from the under side of the piston before the latter reaches the upper end of its stroke; with this advantage, that a sticking reverse valve will not cause damage to the device, the motive fluid merely blowing into the open 105 by the way of the exhaust ports, thereby removing all pressure from the main cylinder. The exhaust port 6' is connected by a conduit 36 to a port 37 adjacent the right end of valve chamber 9. It will be seen 110 that when the valve disk 38 of the reversing valve comes into engagement with an annular flange 39 on the wall of valve chamber 9, the exhaust flow is cut off from exhaust port 40 leading to an exhaust pipe 41. 115 As soon, however, as the exhaust fluid accumulates sufficient pressure back of the valve 7 (a few ounces pressure being sufficient), it will move the valve 7 from the position shown in Fig. 4 to the position shown in 120 Fig. 2 permitting the exhaust fluid to pass to the pipe 41, and at the same time the valve disk 18 will cut off the supply of motive fluid to the passage 26 which leads to the bottom end of the cylinder 3. At the 125 same time fresh motive fluid is admitted to the upper end of the cylinder by way of the passage 19 as soon as the cut off valve 8 passes back to its original position as shown in Fig. 2. It will be seen therefore, that 130

the upstroke is entirely automatic, but that the downstroke is at once automatic reversing, automatic cut-off controlled and controlled by hand valve.

- 5 In the use of the device the control valve 30 may be previously adjusted, or adjusted while it is working, to vary the outlet opening, and thus vary the force of the impact by varying the outflow of the entrapped 10 fluid from beneath the piston 4, and the instant of cut-off of motive fluid and thus likewise the instant of admission of motive fluid to the lower side of the cylinder 3, as well as the expansive action of the motive 15 fluid. If the valve 30 is so throttled that it is almost closed, pressure will quickly rise beneath piston 4 after said piston has passed exhaust port 6 and trapped the remaining fluid in the lower chamber of cylinder 3 causing the cut off valve 8 to move to a full cut off position, piston 4 will therefore move downwardly by the expansive action of the motive fluid thereby striking a softer blow than would be the case if the 25 cut off had occurred later or not at all. The "backpressure" so created is but nominal and does not rise above a few pounds. If the control valve 30 is set wide open the fluid pressure beneath piston 4 will not be 30 sufficient to shift the cut off valve to the closed or cut off position; no cut off will take place and the piston 4 will be reversed without being able to strike an unrestricted blow, since the opening of the exhaust passage 6 near the completion of the downstroke has permitted the fluid pressure to exhaust and thereby to shift the reverse 35 valve 7 into the "up" position, causing the hammer to move upward, thereby repeating 40 the performance.

To further illustrate this device: Assuming that piles are to be driven into soil soft at first, then harder, until finally shale be struck: the control valve would be set nearly 45 shut with the result that with a very early cut-off the ram would strike soft blows far apart (but few a minute). This then would permit the dead weight of the hammer to come into play by following each stroke, with a slide so to say. When harder ground 50 is reached, the control valve is opened wider, with the result that the cut-off will take place later and the stroke will be more powerful. As soon as the shale is struck the hammer without adjustment will strike quicker blows because the downgoing piston will come practically to a standstill as soon as the pile is struck, following hardly any after that; with the result that the 55 cut off valve will return quicker, causing more rapid blows. The operator may now try and open the hand valve still farther, when a full blow will be struck with cut-off taking place near the end of the stroke, 60 or the full available pressure will act upon

the piston, which delivers then its utmost force.

Having described fully my invention but without limiting myself to the particular structure or application here shown, what I claim is:

1. In mechanism of the character described, the combination of a cylinder, a reversing valve, and a fluid pressure controlled valve independent of said reversing valve to control the inflow of motive fluid to said cylinder.

2. In mechanism of the character described, the combination of a cylinder, a piston therein, a reversing valve, a fluid pressure controlled valve independent of said reversing valve to control the inflow of motive fluid to said cylinder and means for controlling the fluid pressure which controls said last named valve.

3. In mechanism of the character described, the combination of a cylinder, a piston therein, a reversing valve, a fluid pressure controlled valve independent of said reversing valve to control the inflow of motive fluid to said cylinder and hand-operated means for controlling the fluid pressure which controls said last named valve.

4. In mechanism of the character described, the combination of a cylinder having inlet ports near each end and exhaust ports near the middle of the cylinder to secure unidirectional flow of the pressure fluid in the cylinder, a piston in said cylinder, a reversing valve and a fluid pressure controlled valve to control the inflow of motive fluid to the cylinder.

5. In mechanism of the character described, the combination of a cylinder having inlet ports near each end and exhaust ports near the middle to secure unidirectional flow of the pressure fluid in the cylinder, the latter ports connected to actuate the reversing valve by the exhaust from the cylinder, a reversing valve, and a fluid pressure controlled valve to control the inflow of motive fluid to the cylinder.

6. In mechanism of the character described, the combination of a cylinder having inlet ports near each end and exhaust ports near the middle to secure unidirectional flow of the pressure fluid in the cylinder, the latter ports connected to actuate the reversing valve by the exhaust from the cylinder, a reversing valve, and a piston having recesses alining with said exhaust ports at opposite ends of its movement.

7. In mechanism of the character described, the combination of a cylinder having inlet ports near each end and exhaust ports near the middle to secure unidirectional flow of the pressure fluid in the cylinder, the latter ports connected to actuate the reversing valve by the exhaust from the cylinder, a reversing valve, a piston having

recesses alining with said exhaust ports at opposite ends of its movement, and means for keeping said recesses in line with said exhaust ports.

8. In mechanism of the character described, the combination of a cylinder having inlet and exhaust ports, a piston reciprocating in said cylinder, a reversing valve, and a valve controlling the inflow of motive fluid to the cylinder, and itself actuated in one direction by a constant yielding force, and in the other by pressure of fluid trapped in the cylinder on the working stroke of the piston.

9. In mechanism of the character described, the combination of a cylinder having inlet and exhaust ports, a piston reciprocating in said cylinder, a reversing valve, a valve controlling the inflow of motive fluid to the cylinder, and itself actuated in one direction by a constant yielding force, and in the other by pressure of fluid trapped in the cylinder on the working stroke of the piston, and means for controlling the last mentioned fluid pressure.

10. In mechanism of the character described, the combination of a cylinder, having inlet and exhaust ports, a piston reciprocating in said cylinder, a reversing valve actuated by the exhaust fluid, a valve controlling the inflow of motive fluid to the cylinder and controlled in one direction by the live motive fluid and in the other by the exhaust motive fluid.

11. In mechanism of the character described, the combination of a cylinder having inlet and exhaust ports, a piston reciprocating in said cylinder, a reversing valve actuated by exhaust fluid, a valve controlling the inflow of motive fluid to the cylinder, and variable means for operating said valve on the working stroke of the piston.

12. In mechanism of the character described, the combination of a cylinder having inlet and exhaust ports, a piston recipro-

cating in said cylinder, a reversing valve actuated by exhaust fluid, a valve controlling the inflow of motive fluid to the cylinder, variable means for operating said valve on the working stroke of the piston, and invariable means for controlling said valve on the return stroke of the piston.

13. In mechanism of the character described, the combination of a cylinder having inlet and exhaust ports, a piston reciprocating in said cylinder, a reversing valve actuated by exhaust pressure, a valve controlling the inflow of motive fluid to the cylinder, means for operating said valve on the working stroke of the piston by the exhaust motive fluid, and means for varying the action of such fluid on said valve on the working stroke.

14. In mechanism of the character described, the combination of a cylinder having inlet and exhaust ports, a piston reciprocating in said cylinder, a reversing valve, a valve for controlling the inflow of motive fluid to the cylinder, invariable means for controlling the latter valve on the reverse stroke of the piston, means for controlling said valve automatically on the working stroke of the piston by variable fluid pressure produced by such working stroke, and means for varying such fluid pressure.

15. In mechanism of the character described, the combination of a cylinder having inlet and exhaust ports, a piston reciprocating in said cylinder, a reversing valve, a valve for controlling the inflow of motive fluid to said cylinder, fluid pressure means for controlling the position of said last named valve to control the point of cut off having means for maintaining the position of the said valve independent of a change in position of the reversing valve.
